OPPOSED-ANGLE BRUSH HOLDER

Gerhard P. Lessmann, Wilkinsburg, Pa., assignor
to Westinghouse Electric Corporation, East
Pittsburgh, Pa., a corporation of Pennsylvania

Application November 6, 1943, Serial No. 509,250

2 Claims. (Cl. 171—324)

My invention relates to brushholders for holding two brushes in operative relation to a rotating commutator, at opposed angles with respect to the radial direction, so that the brushholders can be used, without change or adjustment, on dynamo-electric machines having both directions of rotation.

Brushholders having two (or more) brushes (two in the circumferential direction), have a great advantage over single-brush brushholders, in that any roughness or elevation in the commutator-surface will not strike two circumferentially displaced brushes simultaneously, and hence the entire current will be carried, momentarily, by one brush while the other brush jumps off of the commutator-surface due to roughness.

Heretofore, two-brush brushholders have been of two types, and both have suffered disadvantages. In one type, the two brushes have been parallel to each other, the brushholder had to be taken off and remounted to accommodate a reversed direction of rotation, two springs were required for the two brush-fingers, the spring-pressure was not well compensated against changes due to the amount of brush-wear, and the number of parts, and hence the cost, were excessive. In the other type, the two brushes were at opposed angles, so that the machine could rotate in either direction, a single spring was sometimes used for the two brush-fingers, and the number of parts was reduced, but the spring was not compensated against the effects of brush-wear, so that the pressure on the brush decreased excessively as the length of the brush became smaller because of wear, and there were also other disadvantages, such as excessive lateral pressure on the brushes.

It is an object of my present invention to provide an improved V-type or opposed-angle double-brush brushholder utilizing a linearly acting spring which is connected to the brush-finger, or to both brush-fingers, at such a position and angle that the change in the leverage or moment-alarm of the spring automatically compensates the finger-pressure for practically constant brush-pressure against the commutator, within very narrow limits, during the entire life of the brush. No spring-adjustment is required, therefore, during the life of the brush, to make up for wear or to compensate for the reduced spring-pressure or for altered angle of application of the brush-finger pressure, as the brush-finger follows up the brush as the brush wears away.

Other objects of my invention are to provide a new double-brush brushholder which can be manufactured at less cost than either of the present or previously known common types of double-brush brushholders, and which has numerous other important advantages, among which may be mentioned:

(a) A design suitable for either casting or fabrication from sheet-metal.

(b) Only one shape of finger is required, not a separate finger for right- and left-hand mounting.

(c) The compensating leverage previously mentioned.

(d) The arrangement permits the removal and exchange of either brush without disturbing the other brush.

(e) One old brush and one new brush may be used, without choice of position.

(f) In replacing a worn or defective brush, the brush-finger pulls over-center when lifted off of the brush, and thus locks itself in its elevated position, freeing one hand for the exchange of brushes.

(g) The new brushholder fits old brush-rigging interchangeably with old holders.

(h) The center part of the new holder can be made the same for all sizes of brushes, thus reducing the number of patterns or tools.

(i) It has a reduced number of parts.

(j) For (brush-to-radius) angles of 25° and up, only one spring is used, to provide pressure for both brush-fingers.

Three exemplary forms of embodiment of my new brushholder are shown in the drawing, wherein Fig. 1 is a top plan view of a two-gang V-type brushholder utilizing only one spring for the two opposed-angle brushes, one of the "gangs" or brushholders being shown empty; Fig. 2 is a side-elevational view of the brushholder shown in Fig. 1; Fig. 3 is a side-elevational view of a V-type brushholder having an angle of less than 25° and consequently utilizing two springs for the two brush-fingers; and Fig. 4 is a view similar to Fig. 3, illustrating the equivalence of a compression spring in place of a tension spring.

In the form shown in Figs. 1 and 2, two brushholders 1 and 2 are placed side-by-side, with only one mounting-pad 6, in what is known as a two-gang brushholder. To facilitate the illustration, one brushholder, 1, is shown bare, in Fig. 1, without any loose or movable parts. Each brushholder proper comprises a V-shaped center part 7, having an angularly disposed or inclined brushbox 8 on each side, and having upstanding finger-

supporting arms 10 which are notched at 12 to receive the pivot-pins 14.

Associated with each brushholder proper, are two identical brush-fingers 16, of which only one will be described, and the reference-numerals will be applied only to it, so that its outline may be more readily traced. It has a U-shaped mounting-portion 17, carrying the laterally extending pivot-pins 14. From one side or leg of the U, there extends a downwardly curving finger-arm 18, the tip 19 of which is bent, for engagement with the top of the brush 21. Each finger 16 has its pivot-pins 14 seated in the notches 12 in one side of the brush-holder, and it has its finger-arm 18 extending over to the far brush 21, so as to obtain as long a finger-arm as possible.

It is an important feature of my invention that I utilize a linearly acting spring 23, which is so connected to the brush-fingers 16 that its leverage changes, as the finger swings in following up the brush as it wears on the commutator 24, thus automatically compensating for brush-wear, as previously mentioned.

In the form of my invention shown in Figs. 1 and 2, only one spring 23 is used for the two brush-fingers 16, and the spring is a tension-spring. Each finger 16 has an upstanding rear-portion 25 of the U-shaped mounting-portion 17, and said upstanding rear-portion 25 is provided with two notches 26 and 27, either one of which may be utilized to seat a cross-pin 28 which carries one end of the spring 23, in one notch or the other according to the spring-tension desired.

It will be noted that the center-line of the spring 23 lies above the pivot-point 14 of each finger 16, thus providing a moment-arm for the linearly applied spring-force, tending to rotate the finger-arm 18 downwardly. It will further be noted that the lever-arm, from 14 to 26, extends backwardly, as well as upwardly, so that, as the finger-arm 18 swings downwardly, following the top of the brush 21 as the brush wears on the commutator 24, the rear end 26 of the spring 23 swings upwardly, increasing the spring-moment or vertical distance between the center-line of the spring and the finger-pivot 14. This is the automatic pressure-compensating feature of which I have spoken. Without it, the brush-pressure would fall off quite considerably as a result of brush-wear.

When the finger 18-19 is lifted off of the brush 21, as for the purpose of replacing the brush, the rearwardly inclined spring-lever-arm 26-14 again makes itself felt, because the spring-terminal 26 swings downwardly until the center-line of the spring falls slightly below the finger-pivot 14, thus locking the finger in its elevated position, as shown in dotted lines at 19', so that the operator will not need to use one hand to hold up the finger while he replaces the brush. At the same time the spring is only slightly extended, so that the spring-tension on the other finger is only slightly increased while the first finger is in its locked elevated position 19', thus not interfering with the operation of the other brush, while the defective brush is being replaced.

In common with modern practice, reaction-type brushes 21 are utilized, having inclined or wedge-shaped top-pieces 29 so that the pressure of the finger-tip 19 will have a component or reaction tending to hold one side of the brush against one side of the box 8, thus avoiding rattling or chattering of the brush.

By utilizing a construction in which the finger-arm 18 is long, I reduce the length of arc through which the finger must swing during the useful life of the brush, and I avoid obtaining excessive lateral pressures on the brush at either extreme position of the finger.

Other advantageous features of the operation of my brushholder will be obvious from the construction shown in Figs. 1 and 2, and from the statement of the nature and objects of my invention.

In Figs. 3 and 4, I illustrate a manner in which my invention may be applied to V-type brushholders in which the brush-to-radius angle is too small to readily provide room for the overlying brush-fingers and single-spring construction of Figs. 1 and 2. In Figs. 3 and 4, the fingers 16

20 are mounted on laterally extending arms 31 on the brush-boxes 8', the finger-pivot being indicated at 14'. Because of this arrangement, a separate spring 32 is provided for each brush-finger 16'. As in the single-spring design of Figs. 1 and 2, the spring may be either a tension spring 32, as shown in Fig. 3, or a compression-spring 32', as shown in Fig. 4. In either case, the line of action and the spring-lever-arm are so chosen as to have the pressure-compensating advantages, 25 and the over-center, locked, elevated finger-position feature already described.

While I have illustrated my invention in three preferred forms of embodiment, these forms are nevertheless only illustrative, as many changes 40 may be made without departing from some of the broader features and advantages of my invention. I desire, therefore, that the appended claims shall be accorded the broadest construction consistent with their language.

45 I claim as my invention:

1. An opposed-angle double-brush brushholder comprising a V-shaped center part, an inclined brush-box on each side thereof, two upstanding finger-supporting arms, one on each side of the brushholder, two fingers, each finger being pivot-50 ed on the finger-supporting arm on one side of the brushholder and extending over to the brush-box on the other side of the brushholder, each finger having an extended, downwardly curved 55 finger-arm having a finger-tip adapted to engage the top of a brush, and a linearly acting spring having its respective ends in engagement with the respective fingers for biasing the fingers toward the respective brushes.

60 2. The invention as defined in claim 1, characterized by said two fingers being identical and interchangeable, each finger having a laterally disposed brush-tip portion for engagement with the top of a brush.

65 GERHARD P. LESSMANN.
